UNITED STATES PATENT OFFICE.

LEOPOLD MÄY, OF UNGARISCH-OSTRA IN MORAVIA, AUSTRIA.

REAPING-MACHINE.

SPECIFICATION forming part of Letters Patent No. 236,346, dated January 4, 1881.

Application filed March 29, 1879.

To all whom it may concern:

Be it known that I, LEOPOLD MÄY, of Ungarisch-Ostra in Moravia, Empire of Austria, have invented a certain new and useful Improvement in Reaping-Machines or Improved Reaping-Machine, of which the following is a specification.

The object of the invention is to form a simpler, lighter, and stronger reaping-machine; and it consists in certain details of construction and combination of parts, as herein-after more fully described.

With reference to the accompanying drawings, Figure 1 is a vertical, and Fig. 2 a horizontal, section with parts broken away. Fig. 3 shows the levers for controlling the rake and reel mechanism. Figs. 4 and 5 are other views of parts of the machine. Figs. 6, 7, 8, 9, 10, 11, and 12 show parts of the rake and reel mechanisms. Fig. 13 is a side view, and Fig. 14 a plan view, of the entire machine.

In all the figures the same letters or numbers indicate the same parts—that is to say:

A, main road-wheel; B, vertical frame or standard; C large, and D small, bevel-wheel; E, cutter-crank plate; F, platform; G, small road-wheel; H, vertically-adjustable bracket; J, horizontal bevel-wheel; K, rakes or feed and delivery arms; L, cam-plate; M, clutch; 1, hub of the main road-wheel; 2, hollow axle; 3, bevel-pinion on the crank-plate; 4 and 5, pivot-pins; 6, crank-pin; 7, connecting-rod; 8, cross-head of the connecting-rod; 9, knife-bar or cutter-bar; 10, fingers on the finger-beam; 11, finger-beam; 12, upright of U section; 13 and 14, inclined bars for raising and dividing the standing corn; 15, small roller; 16 and 17, bearings; 18, screw-spindle wheel; 19, axle; 20, hole in the finger-beam, through which the axle 19 is passed when the platform is turned up; 21, hinge-joint; 22, lock-bolt; 23, pin on standard B; 24, brackets; 25, ends of the arms K; 26, rollers; 27, segment of the cam-plate L; 28, bolt; 29, arm or lever; 30, spindle; 31, slot in the segment 27; 32, slot in the cam-plate L; 33, rod; 34, rod; 35, link; 36, lever and fork actuating the clutch; 37, segment of the spindle 30; 38 and 39, holders on the rods 33 and 34; 40 and 41, hand-levers; 42, cross-piece on the lever 43; 45, draft-pole; 46 and 47, brackets or straps; 48, connecting-bolt;

49, hand-lever; 50, link; 51, quadrant; 52, fastening-pin; 53, cutter-bar plate; 54, driver's seat; 43, horizontal lever or arm, and 44 segment on the lever 43.

A vertical frame or standard, B, has a hollow axle, 2, projecting from its outer side, on which is mounted the large road-wheel A, while on its inner side it carries a vertically-adjustable bracket, H, the end of which curves downward and is connected by a hinge-joint, 21, to the inner end of the cutter-beam 11 of the platform F, the outer end of which is supported by the small road-wheel G. The platform F is thus capable of being turned up on its hinge-joint 21 to a vertical position, so that the machine may occupy very little width when passing along narrow roads. For this purpose the bolt 22 is withdrawn, and the small road-wheel G is removed from its axle on the platform F and is placed on one, 19, provided on the bracket H, after turning up the platform, so that the end of the axle 19 projects through the hole 20. The outer end of the curved bracket H is supported on the ground by a small roller, 15. It is made vertically adjustable, so as to regulate the height of the knife-bar 9, by means of a hand-wheel, 18, on a screw-spindle screwing through the bracket H and carried in bearings 16 and 17 on the frame or standard B.

On the extended hub 1 of the main road-wheel A is a large and a small bevel-wheel, C D, both formed in one casting, running loose on the boss, but capable of being geared there-to by a sliding clutch, M.

The large bevel-wheel C gears with a bevel-pinion, 3, formed on the crank-plate E, that works the cutter-bar 9, the latter being connected to the crank-pin 6 by a pitman-rod, 7, formed of two separate rods, 7 7, whose inner ends are pivoted to a head connected by a strap-bolt to the crank-pin, while the outer ends are connected to the cutter-bar by a universal joint, so as to allow of the platform F with the bar 9 being turned up, as before described, without having to disconnect the pitman-rod 7. When in this position the clutch which drives the bevel-wheel C, imparting motion to the cutter-bar 9 from the road-wheel A, is put out of gear by means of a rod, 33, passing through the hollow axle 2 of the latter, and

connected to a lever, 40, at its outer end, while the inner end is connected to a lever, 36, and fork actuating the clutch M. The axle 2 has fixed on its outer end a strong horizontal lever or arm, 43, the end of which is connected by a link, 50, to a hand-lever, 49, pivoted to a bracket, 47, on the draft-pole 45. Thus, on raising the hand-lever 49 the arm 43 is moved so as to turn the axle 2, and with it the frame and platform carried thereby, in such a manner as to cant the front of the platform F, and consequently the cutter-bar 9, up from the ground, so as to make them clear any stones or other obstructions on the ground while reaping. By depressing the hand-lever 49 the knife-bar is canted downward, so as to cut the corn at any desired height. When adjusted to the desired position the hand-lever 49 is fixed by a pin passing through a quadrant, 51, on the before-mentioned bracket 47 of the draft-pole 45. This bracket projects from the outer side of the draft-pole, and is curved round the large road-wheel, A, so as to embrace the end of the axle projected beyond the latter. Another bracket or strap, 46, fixed to the draft-pole embraces an extension of the hollow axle 2 on the inner side of the standard B, so that the draft-pole 45 is carried at the level of the axle.

30 The smaller one, D, of the two before-mentioned bevel-wheels on the axle 2 gears with a horizontal bevel-wheel, J, carried by the standard, and having on the circumference of its upper side a number of brackets, 24, to 35 which are pivoted the reel and rake arms or rakes K, that are thus made to revolve over the platform F for feeding the corn to the cutter-bar 9 and then delivering the cut corn from the platform F. These arms are formed 40 of wood bent into the form of loops, to the lower part of which are fixed rake-teeth. The ends 25 of the arms, beyond their pivots, carry rollers 26, which bear upon a fixed cam-plate, L, which is carried by the standard B, and is 45 of such a shape that as the rakes K pass round they are raised to a vertical position when passing the standard, the driver's seat, and the horses, and are made to descend as they approach the cutter-bar, after which they pass 50 horizontally over the platform and are then raised again.

The cam-plate L has a movable hinged part, 27, which, by means of a spindle, 30, and arm 29, working in a slot, 31, therein, can be raised 55 or lowered, so as to cause the reel or rake arms either to maintain their horizontal position in passing over the platform F, and thus deliver the corn as it is cut, or to be suddenly raised again after passing the cutter-bar 9, so 60 as to allow the cut corn to accumulate to any desired extent on the platform F before delivering it. This action is regulated by the driver by means of a hand-lever, 41, connected to a second rod, 34, passing through the hollow 65 axle 2, and connected at its inner end to the before-mentioned spindle 30, that works the movable part of the cam-plate L.

At the outer end of the finger-beam is fixed an upright, 12, of U-shaped section, which serves as attachment for the bracket of the axle to the small road-wheel G, and also for the inclined bars 13 14, that serve to raise and divide the standing corn.

I claim—

1. In a reaping-machine, the combination, 75 with the main frame B, having hollow axle 2, the drive-wheel A, the bevel-wheels C D, pinion 3, crank-plate E, pitman 7, and the cutter-bar, of mechanism, substantially as described, to throw the cutter-bar out of gear with the 80 main drive-wheel through the medium of a clutch, M, when said cutter-bar and parts connected therewith are to be tilted to a vertical position and hung from the main frame, substantially as described. 85

2. The combination, with the main frame, cutter-bar, grain-platform, and finger-beam having opening 20, and the grain-wheel G, of an intermediate supporting-bracket, to which said finger-beam is hinged, and the axle 19, 90 that passes through said opening 20, and is provided with a bearing for said grain-wheel when removed from the platform, and the latter, together with the cutting devices, is tilted to a vertical position, substantially as 95 and for the purpose specified.

3. The combination, with the overhanging adjustable bracket-arm H, the grain-platform, cutter-bar, and finger-beam hinged to said bracket at 21, of the locking-bolt 22, all arranged and operating as shown and for the purposes described. 100

4. The combination of the main frame B, having a hollow axle, 2, the drive-wheel A, the bevel-wheel C, pinion 3, crank-plate E, 105 pitman 7, cutter-bar 9, lever 40, rod 33, clutch M, and lever and fork 36, all constructed to operate substantially as described.

5. In a reaping-machine, the combination of the main frame B, carrying the rake and reel mechanism and having a hollow axle, 2, the arm 43, bracket 47, link 50, segment 51, lever 49, bracket H, the grain-platform, cutter-bar, and finger-beam hinged to said bracket, as set forth, all arranged and operating to tilt or 110 cant the cutter-bar, for the purpose specified.

6. The combination of the main frame B, provided with a tubular extended axle, 2, the draft-pole 45, the strap 46, bracket 47, tilting-rod 48, levers 43 and 49, link 50, and segment 120 51, all combined, arranged, and operating substantially as shown, and for the purpose specified.

7. The combination of the main frame provided with a tubular axle, 2, the adjustable 125 bracket H, the main drive-wheel A, having an extended tubular hub, the bevel-wheels C D, cast in one piece, mechanism, substantially as described, for operating the cutter-bar and rake-arms, the clutch M, rod 33, lever and fork 130 36, and hand-lever 40, all arranged, constructed, and operating substantially as and for the purposes specified.

8. The combination, with the rake-arms, op-

erating as described, and the slotted cam-plate L, of the pivoted segment 27, slotted at 31, and mechanism, substantially as set forth, for operating the segment to change the path of the rake-arms, substantially as and for the purpose specified.

9. The combination, with the rake-arms, operating as described, and the cam-plate L, slotted at 32, of the pivoted segment 27, slotted at 31, the arm 29, spindle 30, crank 37, rod 34, hand-lever 41, and the main frame having a tubular axle, 2, all arranged, constructed, and operating substantially as and for the purposes specified.

10. The combination of the rake-arms car-

rying wheels 26, the bevel-wheel J, the cam-plate L, the main frame B, having a tubular bearing for said bevel-wheel and cam-plate, and the hollow axle 2, the bevel-wheels C D, cast in one piece, the drive-wheel A, the clutch 20 M, lever and fork 36, rod 33, and lever 40, all arranged, constructed, and operating substantially as and for the purpose specified.

In witness that I claim the foregoing I have hereunto set my hand this 4th day of February, 1879.

LEOPOLD MAÝ.
